CLAIM

The ornamental design for a wall pocket file, as shown and described.

DESCRIPTION

FIG. 1 is a top, front, and left side perspective view of a wall pocket file showing our new design;

FIG. 2 is an enlarged front elevational view thereof;

FIG. 3 is an enlarged rear elevational view thereof;

FIG. 4 is an enlarged top plan view thereof;

FIG. 5 is an enlarged bottom plan view thereof;

FIG. 6 is an enlarged right side elevational view thereof, the left side being a mirror image of that shown; and

FIG. 7 is an enlarged vertical cross-sectional view thereof, taken along line 7—7 of FIG. 1.

FIG. 1

FIG. 3

FIG. 4

FIG. 5

FIG. 6

FIG. 7
